ATTACHMENT-PLUG.

952,952.

Specification of Letters Patent. Patented Mar. 22, 1910.

Application filed April 13, 1907. Serial No. 367,988.

To all whom it may concern:

Be it known that I, FRANK E. SEELEY, a citizen of the United States of America, residing in Bridgeport, in the county of Fairfield, in the State of Connecticut, have invented a certain new and useful Improved Attachment-Plug, of which the following is a specification.

The object of my invention is to provide a simple and convenient attachment plug with inclosed fuses. This object I attain by the construction hereinafter described.

In the accompanying drawing Figure 1 is a plan view of the body of the plug, with the cap off; Fig. 2 is a section on the line 2--2, Fig. 1, the cap being shown lifted; Fig. 3 is a section on the line 3--3, Fig. 1; Fig. 4 is a section on the line 4--4, Fig. 1, but with the cartridge fuses omitted.

The body of the plug is composed of two parts, an insulating core C carrying the usual Edison terminals D and E and a cup-shaped part A to receive the inclosed fuses F, F', while the removable insulating cap B is of any convenient construction. In the present instance I have shown the cap as provided with a central opening b for the passage of the usual insulated wires, the bared ends of which are to be connected to the plates 5, 5, carried by the cap. These plates have downwardly bent portions carrying screws 6, 6, which enter the upright slotted ends 7, 7, of L-shaped plates 8, secured in the cup A. The other ends of these two plates project into the chambers G, G', respectively in the cup A, and the plates are there provided with spring clips 9, 9, to re-

ceive the inclosed fuses F, F'. The opposite ends of these fuses F, F' are held in clips 10, 10, one of which is carried by a plate 11 and the other by a plate 12, one in one chamber G and the other in the other chamber G'. The plate 11 is to be connected electrically to the screw ring terminal D, while the plate 12 is to be connected to the central terminal E, as by screw rod 13. The two chambers containing the two inclosed fuses are separated from each other by an upright wall 14 of insulating material extending across the cup A, and this wall has a projecting partition 15 to separate the plate 12 from the adjacent plate 8.

I claim as my invention:

An attachment plug having a screw ring terminal and a central terminal with a cup shaped body separated into two chambers by a transverse insulating wall, two plates in each chamber carrying clips for an inclosed fuse, one plate in each chamber connecting with one of said terminals, a cap having plates to connect with the other said plates in the respective chambers, and the wall having a projecting partition 15 between the plate for the said central terminal and the adjacent plate in the same chamber.

In testimony whereof I have signed my name to this specification, in the presence of two subscribing witnesses.

FRANK E. SEELEY.
